CLAIM

The ornamental design for a plant pot holder, substantially as shown and described.

DESCRIPTION

FIG. 1 is a top plan view of the plant pot holder embodying my new design;

FIG. 2 is a bottom plan view thereof;

FIG. 3 is a side elevation view thereof;

FIG. 4 is an end elevational view taken from the right of FIG. 3; and

FIG. 5 is an end elevational view taken from the left of FIG. 3.

The side not shown has substantially the same appearance as the side shown.

FIG. 1

FIG. 2

FIG. 3

FIG. 4

FIG. 5
